UNITED STATES PATENT OFFICE.

LOUIS HANIFORD, OF HANNA, ALBERTA, CANADA.

AUTOMATIC GATE OPENING AND CLOSING DEVICE.

Application filed May 17, 1926, Serial No. 109,771, and in Canada March 30, 1926.

The invention relates to improvements in automatic gate opening and closing devices and an object of the invention is to provide a device embodying normally closed gates which will be automatically opened by an approaching vehicle, train or such like and will be locked open until such time that the vehicle or train has passed and cleared the gates and will then be subsequently freed to close.

A further object of the invention is to arrange the construction such that the gates will be opened and locked open automatically by the train or vehicle when approaching the gates from either side and automatically released to close after having passed the gates.

A further object of the invention is to construct the appliance in a simple, durable and efficient manner and so that there will be little difficulty in installing it say on a railroad at the point of intersection with a highway.

A further object of the invention is to provide the device as utilized on railroads with pairs of gates which are normally closed to prevent passage of wandering animals along the track and upon a train approaching, are automatically opened to positively stop the passage of vehicular traffic along the highway until such time that all point of danger is passed at which time the gates are automatically closed by the passing train.

A further and more specific object of the invention is to provide normally closed gates at the opposite sides of the highway and crossing the track, actuating members located some distance remote from the gates and along the tracks, said members being adapted to be struck by the passing train to open the gates, means for subsequently locking the gates open and pressure plates located between the actuating members and the gates and associated with the rail and adapted to be depressed by the car wheel and designed to positively maintain the gates locked until the car is well past the crossing and then permit the gates to close.

With the above more important and other minor objects in view which will become more apparent as the description proceeds, the invention consists essentially in the arrangement and construction of parts herein-

after more particularly described, reference being had to the accompanying drawings, in which:

Fig. 1 is a plan view of the device showing the gates in the normal or closed position across the track.

Fig. 2 is an enlarged detailed vertical sectional view at 2—2' Figure 1.

Fig. 3 is a vertical cross sectional view at 3—3' Figure 2.

Fig. 4 is an enlarged detailed vertical sectional view at 4—4' Figure 3 and looking in the direction of the applied arrow.

Fig. 5 is a vertical sectional view at 5—5' Figure 4.

Fig. 6 is a perspective view of the actuating shaft, lever and other parts associated therewith.

Fig. 7 is a perspective view showing the operating parts in full outline and certain other parts in dotted outline.

In the drawings like characters of reference indicate corresponding parts in the several figures.

The device herein shown provides gates which are normally closed across the railroad track at a crossing to permit of the passage of vehicular traffic and to prevent animals wandering along the tracks and which are arranged such that upon a train approaching the crossing, said gates will be opened and locked open to stop vehicular traffic and permit the passage of the train and such that after the train has passed the crossing the gates will be unlocked thereby and closed.

Whilst the drawings show the device as used on a railroad, I wish it to be understood, however, that the gates could be employed in any other desirable location as in a building such as a garage and be operated by pressure bars to open and close upon the passing of the vehicle such as an automobile.

Referring now to the drawings, the railroad tracks 1 and 2 are mounted in the usual manner on the ties 3 and at the sides of the crossing 4 I locate similar pairs of normally closed gates 5, 6, 7 and 8, the gates having their outer ends carried by vertical spindles or shafts 5', 6', 7' and 8', the lower ends of which are rotatably mounted in similar suitable stationary boxes 9 provided. The gates have their inner ends just nicely clear of one another so that they are free to operate and

such that when the gates are closed, there can be no passage along the tracks in either direction from the crossing.

Accordingly the closed gates, which are locked as later described, not only prevent the wandering of animals along the tracks but also permit of the safe passage of vehicular traffic as one knows when the gates are so closed, that passage is safe.

- 10 The lower ends of the shafts are fitted with similar bevel pinions 10 and these bevel pinions are continuously in mesh with further bevel pinions 11 located on the ends of similar cross shafts 12 and 13 located one 70
15 at each side of the crossing. The outer ends of the said cross shafts are circular in cross section and have their outer ends rotatably mounted in the side walls of the boxes 9. The central portions of the said shafts are 75
20 square in cross section and the shafts are supported by suitable bearing bars 14 and 15 secured to adjacent ties.

On the square part of the shaft 12, I mount a single pulley 16 and two other 80
25 pulleys 17 and 18 and on the shaft 13, I mount a single pulley 16' opposite that of 16 and two further pulleys 17' and 18' opposite those of 17 and 18. A pulling line or cable 19 connects the pulleys 16 and 16', the said 85
30 cable passing from the under side of the pulley 16 to the top side of the pulley 16'. A turnbuckle 19' is introduced in the cable 19 to allow the adjustment of the same. A pulling line or cable 20 connects the pulley 35
35 17 with that of 17', this cable passing from the top of the pulley 17 to the under side of the pulley 17'. A turnbuckle 20' is inserted for adjusting purposes in the cable 20.

According to this arrangement, it will be 40 apparent that if say the shaft 12 be rotated in the direction of the applied arrow Figure 7, the gates 7 and 8 actuated by the said shaft will be opened and further that the cable 19 will act to rotate the shaft 13 in 45
45 the direction of the applied arrow Figure 7 with the result that the gates 5 and 6 will be simultaneously opened. On the other hand, should the shaft 13 be rotated in the direction of the applied arrow, the gates 5 50 and 6 will open and the cable 20 will operate to rotate the shaft 12 in a direction which will open the gates 7 and 8.

The gates as hereinbefore intimated are 55 opened by a train approaching the crossing and remain open until the train is passed at which time, they are unlocked and free to close. The mechanism actuated by the approaching train for opening the gates and locking the same and the mechanism for 60 releasing the gates to close after the train has passed are the same at either side of the crossing so that I only consider it necessary to herein describe in detail the said mechanisms at one side of the crossing.

65 At a selected distance somewhat up the

track from say the gates 7 and 8, I locate an actuating shaft 21 which has the ends thereof rotatably mounted in bearing bars 22 and 22' carried by adjacent ties. The shaft is fitted with an upstanding lever 23 and a downwardly extending crank 23' and can be provided also with a weighted arm 23''. A pulling line or cable 24 connects the crank 23' to the pulley 18, the said pulling line passing underneath the pulley. A turnbuckle 24' is interposed in the cable for adjusting purposes and in this connection, I might point out that when the gates are closed, the lever extends vertically.

The lever is positioned adjacent the head of the rail 1 so that the flange of the wheel of a train advancing in the direction of the arrow A Figure 1 will strike the lever and swing it downwardly in a direction towards the gates which movement will cause the cable 24 to rotate the shaft 12 to open the gates 7 and 8 and the cable 19 to rotate the shaft 13 in a direction to open the gates 5 and 6. Accordingly the gates are simultaneously opened the instant the lever 23 is 90 knocked downwardly.

It is necessary to lock the gates open after they have been so actuated as it will be observed that each of the shafts 12 and 13 is fitted with a crank 25 to which a spring 95
95 26 is fastened, the spring being also attached to an adjacent tie and being arranged such that after the gates are opened the springs are brought into tension and would accordingly tend to close the same.

The mechanism for locking the gates is now described. On the shafts 12 and 13 I mount similar dogs 26 and 27, these dogs being normally down turned and having their upper portions extending in short lever arms 28 lengthwise slotted as indicated at 28'. Links 29 and 30 are provided, these having their outer ends pivotally secured to an adjacent tie and their inner ends fitted with pins 31 slidably entering the slots 28'. 100
105

Adjacent the rail 1 at opposite sides of the crossing, I locate similar pressure bars 32 and 33 which have the heads 34 thereof immediately to the inner side of the head of the rail 1 and the ends thereof curving downwardly so that the flange of a train wheel will ride and depress them. The pressure bars are provided on the under side with three downwardly extending socket like extensions 35, 36 and 37 and these contain coiled springs 38 which ride the upper ends of similar posts 39, 40 and 41 suitably anchored to the ground. The springs 38 hold the heads of the pressure bars normally in an elevated position as best shown in Figure 5 but it will be obvious that upon a train wheel engaging with and riding over the pressure bar, the said pressure bar will be depressed and held depressed for the entire period of the passage of the train, it being 110
115
120
125
130

understood that the length of each pressure bar is greater than the greatest distance between any two adjacent car wheels.

The socket like extension 36 is provided in each instance with a lug 36' and this lug normally engages with one end of a catch bar 42 which passes transversely across a suitable slot 43 cut in one of the ties and has the other end thereof projecting into the path of travel of the adjacent dog 26 or 27 as the case may be and here it will be observed (see Figure 4) that the one edge of the dog is rounded to permit it to escape past the catch bar when rotating in one direction.

A housing or plate 44 encloses the top and one end of the slot 43 and in the housing I locate a spring 45 which operates to hold the catch bar 42 down in the position shown in Figure 4. It will be observed also that the housing holds the end of the catch bar next the lug from rising although permitting the catch bar to rock. The catch bar is prevented from moving towards the lug by a pin 46 engageable with the housing. The socket like extension 37 is provided with a pin 47 which overlies the adjacent link 29 or 30 as the case may be.

According to the above arrangement, it will be apparent that when the train is approaching the crossing in the direction indicated by the arrow A, it will initially open the gates by striking the lever 23 as hereinbefore explained and in rotating the shafts 12 and 13 will cause the dogs 26 and 27 to move in a direction such that they will initially click past the adjacent ends of the catch bars 42 and then become locked in a position such as shown in dotted outline in Figure 4, with the result that the shafts are locked against rotation and consequently the gates are locked open.

During this locking action the links 29 have an idle down movement, the pins 31 sliding in the slots 28' and the catch bars 42 rock to allow the dogs to go by and then subsequently become caught on the ends of the catch bars. This locking movement takes place before the on coming train reaches the pressure bar 32.

Upon the train engaging the pressure bar 32, it moves down and remains down until the complete train has passed there over. As it moves down, the dog 26 will be released from the catch plate but such release of the dog 26 does not free the shaft 12 to rotate under the action of the spring 26 as the said shaft 12 being connected by the cables to the shaft 13 cannot rotate until the dog 27 controlling the shaft 13 has been unlocked.

I might point out also that although the dog 26 has been released from the catch bar, the pin 47 is operating to hold the link 29 down during the time that the passing

train is on the pressure bar 32 with the result that the shaft 12 cannot rotate.

As the front end of the train reaches the pressure bar 33, it moves it down and releases the dog 27 from the adjacent catch 70 bar but as the train is now on the pressure bar 33, the pin 47 engaging with the link 29 prevents any rotary movement of the shaft 13 and as this shaft is connected to the shaft 12 by the cables, the latter shaft cannot rotate and here I might point out that even after the passing train has completely cleared the pressure bar 32 and both the dog 26 and the adjacent link 29 have been freed, still the shaft 12 cannot turn by virtue of its connection through the cables with the then locked shaft 13.

When the rear car of the passing train clears off the pressure bar 33, the said pressure bar rises and the shaft 13 is then free to rotate under the actions of its spring as is also the shaft 12. The gates accordingly simultaneously close. The lever 48 at the other side of the crossing from that 23 will be swung down when the approaching train strikes the lever 23 as at this time there will be slack in the cable 49 connecting the pulley 18' with the crank 50 corresponding to the crank 23' and the weight corresponding to that 23' and attached to the actuating shaft 51 will drop.

After the passing train has cleared the pressure bar 33, the lever 48 will be brought back to an upstanding position by the closing of the gates but when subsequently struck by the train will only be knocked down and make an idle movement as such will simply cause a slackening of the cable 49. When the train has passed the said lever, the weight associated therewith brings it back to an upstanding position.

I have not considered it necessary to describe the operation of the device when the train is approaching from the opposite direction as the action hereinbefore described would just be duplicated, the opening of the gates being brought about by the contacting of the flange of an on coming car wheel with the lever 48 and the final release of the gates to simultaneously close occurring after the passing train has cleared off the pressure bar 32.

I have also shown plates 52 and 53 attached to the tops of the gates, such plates being warning signals to approaching vehicular traffic. These plates have the word "Stop" indicated thereon. Whilst I have shown plates any type of warning signal could be used. In fact, the device could be used to advantage by substituting signal carrying arms for the gates without departing from the spirit of the invention.

If either of the cables connecting the actuating levers to the operating shafts 12 or 13 should break when the lever is hit by the ap-

proaching train, I might point out that the gates will be opened so that they will not be struck and demolished by the train. After passing the lever, the train will engage the 5 pressure plate and move it down and the pin 47 will swing the link 29 downwardly which will cause the turning of the dog and consequently the turning of the cross shaft 12 or 10 13 as the case may be. The turning of one shaft turns the other on account of the interconnecting cables with the result that both pairs of gates are opened simultaneously and the pair of gates remote from the train are locked open by the associated dog so that 15 those gates nearest the train are also locked open after the train has passed the pressure bar associated therewith.

What I claim as my invention is:—

1. An automatic gate opening and closing device for intersecting railway and vehicular crossings comprising a rotatably mounted cross shaft crossing the railway tracks at either side of the highway and extending there beyond, means connecting the shafts 20 whereby they are compelled to rotate together in opposite directions, a pair of pivoted gates located at either side of the highway and normally closed across the tracks, operating means connecting the cross shafts 25 to the gates whereby, in the rotation of the shafts, the gates simultaneously open and close, spring means connected to the shafts for simultaneously closing the gates, depressible actuating members located adjacent 30 the tracks and adapted to be struck by the passing car wheel, said members being located at some distance from the gates, means connecting the said members to the shafts whereby in the depression of one of said 35 members by the approaching train, the gates are simultaneously opened, locking means associated with each shaft for automatically locking the gates in the open position and depressible locking bars adjacent each pair 40 of gates and the track and engageable when depressed with the several locking means, both of said depressible bars having to be depressed before the gates are released to 45 close.
- 50 2. An automatic gate opening and closing device for intersecting railway and vehicular crossings comprising a rotatably mounted cross shaft located at each side of the highway and crossing the tracks and extending 55 therebeyond, bevel gears secured to the ends of the shafts, vertically disposed rotatably mounted spindles located at the ends of the cross shafts, bevel gears secured to the lower ends of the spindles and in mesh with the 60 former gear wheels, pairs of gates secured to the spindles and taking normally a closed position across the tracks, means connecting the shafts to cause the simultaneous rotation thereof in opposite directions whereby 65 the gates open and close together, depressible

gate opening members located some distance from the pairs of gates and at opposite sides of the highway and adapted to be depressed by the wheel of a train approaching the highway, means connecting the depressible members with the shafts whereby the depression of one of the members causes the simultaneous opening of the gates, locking means adjacent the shafts adapted to automatically and simultaneously lock the several shafts 70 against rotation and upon the gates opening, spring means associated with each shaft tending to close the opening gates, a depressible bar associated with each shaft and positioned to be engaged and depressed by the passing wheel of a train, said locking bars being adapted further upon depression to unlock the adjacent locking means and whilst in such depressed position do themselves prevent the closing of the gates. 80

3. An automatic gate opening and closing device for intersecting railway and vehicular crossings comprising a rotatably mounted cross shaft located at either side of the highway, crossing the tracks and extending 90 there beyond, bevel gears secured to the ends of the shafts, rotatably mounted upstanding spindles located at the ends of the shafts, bevel pinions secured to the spindles and meshing with the bevel gears, pairs of gates 95 secured to the shafts, said gates taking normally a closed position across the tracks, cables and winding pulleys connecting the shafts to cause the simultaneous opening and closing of the gates, a normally upstanding, pivoted, actuating lever located at some distance from the gates at either side of the roadway and positioned to be struck down by an approaching train wheel, further winding pulleys secured to the cross shafts, 100 pulling lines connecting the levers with the latter pulleys whereby upon one or other of the levers being knocked down by a wheel approaching the gate, the gates are simultaneously opened, means associated with each shaft for automatically locking the shaft against rotation upon the gates being 105 opened, a depressible pressure bar adjacent each shaft and extending in a direction away from the gates and positioned to be depressed by a passing train wheel and upon depression to unlock the adjacent locking means and subsequently to prevent through said locking means, the closing of the gates until the passing train has cleared both of said 110 pressure bars, and spring means subsequently closing the released gates. 115

4. The combination with a railway crossing of a gate movable about a vertical pivot located at one side of the track to extend either across the rails of the track or across the intersecting roadway, means for normally retaining the gate in a position extending across the rails of the track whereby said gate functions as a cattle guard, train con- 120 125 130

trol means for swinging the gate from normal position to a position extending across the intersecting roadway, said train control means including provision for locking the gate in the last mentioned position while the train is passing the crossing and for automatically releasing the gate when the train has cleared the crossing to permit the gate to return to normal position.

10 5. A combined cattle guard and crossing gate for railway tracks comprising vertically disposed gate posts rotatably mounted at opposite sides of the track and at opposite sides of the roadway intersecting the track, gates

15 carried by said posts and rotatable there-

with to swing in a horizontal plane, means for normally retaining said gate in a position extending across the rails of the track to form a cattle guard and train control means functioning when a train approaches 20 the crossing to swing the gates clear of the track and to a position forming a barrier across the intersecting roadway, said train control means functioning to lock the gates in the last named position until the train 25 has cleared the crossing.

Signed at Hanna this 1st day of March, 1926.

LOUIS HANIFORD
